Specification for Design.

Patented Oct. 17, 1916.

Application filed July 8, 1916. Serial No. 108,206. Term of patent 14 years.

To all whom it may concern:

Be it known that I, JAMES C. DOUST, a subject of the King of Great Britain, and a resident of the city of Toronto, in the county of York, Province of Ontario, Dominion of Canada, have invented a new, original, and ornamental Design for Rake-Heads, of which the following is a specification, reference being had to the accompanying drawing, forming part thereof.

Figure 1 is a plan view of a rake head, Fig. 2 a rear elevation and Fig. 3 an end elevation of the same, showing my new design.

I claim:

The ornamental design for a rake head, as shown.

JAMES C. DOUST.
